APPARATUS FOR HOLDING SANITARY
SEAT COVERS

James H. Shelley, Beverly Hills, Calif., assignor,
by direct and mesne assignments, to California
Fruit Wrapping Mills, Inc., a corporation of
California

Application April 20, 1934, Serial No. 721,486

3 Claims. (Cl. 206—57)

This invention relates to an apparatus for holding and facilitating the individual delivery of sanitary seat covers, such as employed for covering the seats of toilets.

One of the objects of the invention is to provide simple means for holding a pack of the seat covers in such a way that the removal of the seat covers, one by one, is facilitated.

A further object of the invention is to provide an apparatus of this kind constructed in such a way as to facilitate the supplying of the seat covers in a pack mounted in a holder, the holder being constructed so as to enable a portion of the foremost seat cover of the pack to be exposed at an opening and so that the foremost seat cover can be readily withdrawn from the holder through the opening; and to accomplish this without disturbing the seat covers constituting the remainder of the pack.

A further object of the invention is to provide a holder of simple construction for carrying a pack of seat covers and having a construction enabling it to cooperate with a rigid outer holder in which the same can be readily placed, said holders being correlated in construction so as to facilitate the removal of the seat covers, one by one, as desired for use.

Further objects of the invention will appear hereinafter.

The invention consists in the novel parts and combinations of parts to be described hereinafter, all of which contribute to produce an efficient apparatus for holding sanitary seat covers.

A preferred embodiment of the invention is described in the following specification, while the broad scope of the invention is pointed out in the appended claims.

In the drawing:

Figure 1 is a perspective of a holder for carrying a pack of seat covers, and particularly illustrating a means employed on this holder for increasing the accessibility of the seat covers carried therein.

Figure 2 is a front elevation of a complete apparatus which includes an outer holder in which an inner holder may be placed carrying a pack of the seat covers.

Figure 3 is a vertical section, taken on the line 3—3 of Figure 2, but upon an enlarged scale.

Figure 4 is a plan of one of the seat covers removed from the pack.

Figure 5 is a vertical section through one of the seat covers and showing the same in a position which it has in the pack held within the holder.

Figure 6 is a fragmentary view and is a vertical section taken through one of the upper corners of the holder and illustrating another embodiment of the invention as regards the means for suspending the pack of seat covers.

Figure 7 is a fragmentary view and is a vertical section taken through the lower portion of a holder, and illustrates means which I prefer to employ for securing the lower ends of the seat covers when the embodiment of the invention illustrated in Fig. 6 is employed.

Before proceeding to a more detailed description of the invention, it should be stated that in practising my invention I provide a holder for a pack of seat covers. This holder may constitute the only holder for the seat covers, but in practice I prefer to provide an inner holder and an outer holder. The inner holder then operates as an envelope for carrying a pack of the seat covers, and in practice this holder is slipped into position in a more substantial outer holder, preferably constructed of sheet metal and which is secured to a support in the vicinity of the toilet.

Referring more particularly to the parts, I indicates a holder which preferably constitutes the inner holder, and this holder is preferably in the form of a box form envelope, into which the pack of seat covers is introduced. If this holder were formed of rigid material, such as metal, it could be employed as the only holder for the pack. However, I prefer to mount this inner holder 1 in an outer holder 2 (see Fig. 2). This outer holder is preferably formed of sheet metal and is provided with a removable cover 3, which can be taken off to permit the inner holder 1 to be dropped into the outer holder. The outer holder 2 on its forward wall is provided with a delivery opening 4, which at its lower edge is preferably provided with an outwardly projecting lip 5 to facilitate the withdrawal of the seat covers 6, as will be described hereinafter. These seat covers are substantially of rectangular form, as illustrated in Fig. 4, but formed with a large U-shaped incision 7, which forms a flap 8 which is adapted to be shoved down into the opening of the toilet seat to assist in retaining the seat cover in position.

The forward edge of each seat cover is formed into a tongue 9 with a curved forward edge 10.

In the embodiment of the invention illustrated in Fig. 3, the seat covers are all placed together to form a pack 11 carried in the inner holder 1, and before being placed in this pack each seat cover is folded on a transverse line at about the position of the dotted line 12 of Fig. 4. In put-

ting the seat covers together to form a pack, the tongues 8 of the seat covers are disposed toward the opening 4. In order to improve the efficiency of the inner holder 1, its forward wall is preferably provided with a weakened panel 13, the outline 14 of which is partially cut through so as to facilitate its detachment from the wall to form an opening 15 (see Fig. 3), which substantially registers with the aforesaid delivery opening 4. 10 In this way, when the inner holder has been put in position, the tongue 8 of the foremost seat cover in the pack will be exposed at the delivery opening 4 so as to facilitate its being seized to facilitate the withdrawal of the foremost seat cover.

In order to support the seat covers in the form of pack 11, I prefer to provide means for suspending the same at an elevated point. For this purpose, I may employ a cross-pin 16 (see Fig. 3), which passes through all of the seat covers and has its ends secured in the forward and rear side walls of the inner holder.

In order to save material and reduce the weight of the outer holder 2, I may provide the same with a large opening 17 on the forward side, and, if desired, metal may be punched out from the rear wall 18 for the said purpose. The outer wall, however, should have a transverse bar 19 near its middle point through which fastening devices, such as nails or screws 20, may be applied to fasten the outer wall to a support.

In order to facilitate the dislodgment of the weakened panel 13, I may provide its lower edge with a finger hole 21 (see Fig. 1).

It will be evident that by seizing the tongue 8, which is exposed at the delivery opening 4, the outermost seat cover can be readily pulled down so as to detach its upper and folded edge from the suspending pin 16. The cover can then be readily withdrawn through the opening 4 without disturbing the other seat covers in the pack.

In Figs. 6 and 7 I illustrate another embodiment of the invention which has the advantage that it obviates the necessity for individually folding all of the seat covers before putting them into a pack. In this case a pack of the seat covers is formed and they are then folded on a line located at about the position of the line 12 in Fig. 4. In other words, the entire pack is folded on a transverse line. This enables the entire pack to be suspended on a longitudinal horizontal bar 22 which supports the fold 23 of the pack as shown. The ends of this bar are supported in the end walls of the inner holder, as illustrated in Fig. 6.

In forming the pack of seat covers in this way the tongues 24 will all be superposed upon each other, as illustrated in Fig. 7, and they will all be located in the front opening 25 of the inner holder 26. In order to prevent the removal of the seat cover that has the foremost tongue 24 from dislodging any of the other seat covers in the pack, I prefer to provide the lower portion of the pack below the opening 25 with a cross-pin 27. This pin passes through the pack from the front wall of the holder to the rear wall, like the pin 16 illustrated in Figs. 1 and 3. With this arrange-

ment, it will be evident that by seizing the foremost tongue 24 and pulling it downwardly, tension will be exerted on the corresponding seat cover, which will be torn away from the pin 27 and withdrawn through the opening 25 without dislodging any of the other seat covers of the pack.

It is understood that the embodiment of the invention described herein is only one of the many embodiments this invention may take, and I do not wish to be limited in the practice of the invention, nor in the claims, to the particular embodiment set forth.

What I claim is:

1. In a package of seat covers of the kind described, the combination of a holder having a forward wall with a narrow delivery opening at the lower portion thereof, a plurality of seat covers formed of separate sheets, each sheet having a connected flap punched out from the same to form an opening to fit over the seat opening, means located at an elevated point in the holder, and passing through said flaps for suspending the covers in a folded state within the said holder, each cover having a tongue disposed toward the forward side of the holder with its edge located at a point considerably above the lower edge of said delivery opening, and enabling the tongue to be seized through the said opening in detaching the cover from the suspending means.

2. In an apparatus of the kind described, the combination of a holder in the form of an envelope of cardboard to be received within an outer holder and having a forward wall with a narrow opening in the lower portion thereof, a plurality of separate sanitary seat covers carried in the holder, each cover having a folded edge at its upper end, means carried by the holder and passing through the folded edges of the seat covers for suspending the said covers within the holder, each of said covers having a tongue with its lower edge visible through said opening so as to enable the tongue to be seized through the said opening for detaching the cover from the suspending means.

3. In apparatus of the kind described, a holder in the form of an envelope having a forward wall with a narrow opening in the lower portion thereof, a plurality of separate detached seat covers received in said holder, each of said seat covers having a folded edge located at an elevated point in said holder, each seat cover having an integral central flap partially detached therefrom, a transverse pin passing through the walls of said holder and passing through the said flaps of said covers for suspending said seat covers within the holder, each of said seat covers having a tongue toward its lower end, the lower edge of said tongue located considerably above the lower edge of said opening and visible through said opening, and enabling the tongue of the foremost seat cover to be seized to detach the foremost seat cover from the pin and pull the same out through the said opening.

JAMES H. SHELLEY.
